SAMUEL J. DICKEY, OF LOS ANGELES, CALIFORNIA, ASSIGNOR TO GENERAL PETROLEUM CORPORATION OF CALIFORNIA, A CORPORATION OF DELAWARE.

METHOD OF AND APPARATUS FOR TREATING ONE FLUID BY ANOTHER.

Application filed January 16, 1923. Serial No. 613,064.

My invention can be best explained by referring to a concrete example of its use, although it is capable of many uses. For the purpose of illustration, I have selected the treatment of kerosene by acid. Kerosene as it comes from the usual refining process contains many impurities which affect its color and odor and it is a common practice to treat such kerosene with acids and alkalis and to wash it with water for the purpose of improving its color and odor. My invention may be used in various ways in this process but for the purpose of simplicity of description I will describe it as applied to the acid treatment of kerosene without of course limiting my invention to this particular step in the process of refining kerosene.

In the treatment of kerosene with acid, as now practiced in the art of oil refining, the acid is passed through the kerosene which is carried in suitable tanks or agitators. The acid, being heavier than the kerosene, tends to sink into the bottom of the tanks and it is necessary if any considerable degree of commercial efficiency is to be attained that the acid and kerosene be intimately mixed and that they be held in contact with each other for a sufficient period for the acid to act upon the kerosene. This is at present accomplished, to some degree, by the use of agitation in the tanks, this agitation being sometimes produced by blowing air through the mass of acid and kerosene in the tank. The present methods of treating kerosene require large and expensive agitators and the mixture of oil and acid must remain in them for considerable periods thus requiring large investment in such agitators and a correspondingly large loss through depreciation and cost of operation.

It is an object of my invention to provide a method and apparatus by which the kerosene may be treated by acid at a low cost and by which the investment in agitators may be very greatly reduced over that at present necessary when using the commonly employed processes.

The acid by continued contact with the kerosene becomes exhausted forming an acid sludge. The further this exhaustion is carried the lower the cost of acid will be, and it is a further object of my invention to provide a method and apparatus in which the acid may be almost completely exhausted

without requiring a large investment in agitators or a long continued treatment of the kerosene.

Further objects and advantages will be made evident hereinafter.

Referring to the drawings which are for illustrative purposes only,

Fig. 1 is an elevation of a preferred embodiment of the apparatus used in practicing my invention.

Fig. 2 is a plan view of the same.

Fig. 3 is a section through an injector nozzle, and,

Fig. 4 is a section of a multiple stage treat-
er in somewhat diagrammatic form.

Figs. 5 and 6 are diagrammatic views illustrating alternative forms of apparatus with which the invention may be employed.

In the form of treater shown in Figs. 1 and 2, a tank 11 is provided, this tank having a tight bottom 12 and a tight top 13 into which a refined kerosene pipe 14 is connected. A spent sludge pipe 15 having a valve 18 is connected into the tank near its bottom and an acid inlet pipe 16 having a valve 9 passes through the side of the tank near its top terminating in a spray nozzle 17 inside the tank. Connected into the tank tangentially is an inlet header 20 into which are connected a plurality of injector pipes 21, these pipes having a constricted portion 22, as shown in Fig. 3. Each pipe 21 is provided with a nozzle 24 which is connected through a pipe 25 and a suitable valve 26 with a raw kerosene inlet pipe 27.

The pipes 21 are shown as substantially parallel and as connected through pipes 28 and valves 29 with an outlet manifold 30, this outlet manifold being tangentially connected into the tank 11 at a point considerably above the point of contact of the inlet manifold 20.

The method of operation of the apparatus shown in Figs. 1, 2 and 3 when used to treat kerosene with acid is as follows:

The kerosene which it is desired to treat is introduced into the tank 11 through the pipe 27. This pipe connects into the pipes 25, each of which is connected into one of the nozzles 24 as shown in Fig. 3. The oil from the nozzle 24 flows with considerable force through the constricted portion 22 of the corresponding pipe 28 and back through the valves 29 and the header 30 into the tank

11. In its passage through the nozzle 24 and the constricted portion 22 of the pipe 28 the flowing stream of kerosene acts as an injector sucking previously introduced and somewhat mixed liquid from the inlet pipe 20 and forcing it violently into the pipe 28.

12. Acid is delivered into the tank 11 by the pipe 16 and the spray nozzle 17. This nozzle serves to divide the acid and mix it with the kerosene already in the tank 11. It is, however, of only very limited efficiency in this connection and the acid might almost as well be delivered directly into the bottom of the tank 11 by any convenient means not shown. It is however, just as easy to spray the acid in and this spraying is of some value.

13. The acid, however, is only very roughly divided by the spray nozzle 17 and it falls almost immediately into the bottom of the tank 11 due to its much greater specific gravity than oil. As soon as sufficient acid accumulates in the bottom of the tank to 25 reach the level of the inlet pipe 20, this acid is drawn over into the space inside the pipes 21 around the nozzles 24 and by the action of these nozzles is drawn through the constrictions 22 into intimate contact and mixture with the kerosene flowing through these nozzles.

14. The pipes 28 are of graduated sizes and one or more of them can be entirely cut out of service by the use of the valves 26 and 29. These valves are manipulated to suit the amount of kerosene delivered to the pipe 27 by the source of supply in such a manner that a very intense turbulent action is set up in the pipes 28 thus intimately mixing and 40 preventing the separation of the kerosene and acid. The pipes to be put in service for efficient action can be determined by trial and this number is thereafter regulated to suit the quantity of kerosene delivered by 45 the pipe 27.

15. In their passage through the pipes 28, the kerosene and acid form an extremely intimate mixture and this mixture is delivered through the pipe 30 tangentially into the tank 11. Since the pipe 30 and the pipe 20 both enter the tank tangentially but in opposite directions, and since the fluid flows in opposite directions in these pipes, it is evident that their action is cumulative and 55 that they both tend to set up a rotation of the mass of oil and acid in the tank 11, which rotation acts centrifugally upon the kerosene and acid, throwing the heavy acid to the periphery of the tank and the kerosene into the center. The acid falls to the bottom of the tank in a partly exhausted form and is again caught up by the suction of the pipe 20 and redelivered to the pipes 28 where it is again mixed with fresh 65 kerosene and further exhausted. This cen-

trifugal separation is desirable but not absolutely necessary as the kerosene and acid separate readily by gravity.

16. The degree of the final exhaustion of the acid to the acid sludge is determined by the rate at which the acid sludge is continuously drawn off through the pipe 15 which can be regulated by the valve 18 and the rate of flow of fresh acid delivered through the pipe 16 which can be regulated by the valve 9. 75 In practice, the valve 18 is manipulated to give the desired degree of exhaustion of the sludge and the valve 9 is manipulated to maintain a certain level of acid and acid sludge in the tank 11, which can be very 80 readily determined by the gauge glass 31.

17. I believe that the demonstrated efficiency of my invention is due to the high degree of turbulence maintained in the pipes 28 by the use of the nozzles 24 and by a suitable 85 regulation of the valves 26 and 29 which are manipulated to maintain this turbulence. This turbulence intimately mixes the kerosene and acid and allows the acid to act 90 efficiently upon the oil.

18. The treated kerosene flows through the pipe 14 to another treater similar to that shown and described above where it may be further treated with acid, alkali or water.

19. Further economies may be obtained by the apparatus shown somewhat diagrammatically in Fig. 4. In this sketch, 40, 41 and 42 are tanks which are superimposed, one upon the other, being separated by partitions 43 and 44. Three tanks are shown but more or less may be used if found convenient. The kerosene is delivered through a pipe 50 into an injector 51 which is fed acid sludge from a body of sludge shown at 52, the level of this sludge being maintained by means of a 105 valve 53 in a spent sludge pipe 54, by means of a valve 53. The kerosene and acid are mixed in a pipe 55 and are delivered through a distributor 56 into the tank 42. Acid sludge may be continuously drawn off 110 through the pipe 54 and partially treated kerosene is then delivered through a pipe 60 from the top of the tank 42 to an ejector 61 and into a pipe 63 which is fed with sludge, from a body of sludge 64 carried at the bottom of the tank 41, the mixture from the pipe 63 being delivered through a distributor 65 into the tank 41.

20. The level of the sludge in the tank 41 is maintained by a pipe 70, this pipe connecting into the tank 41 at a desired level and delivering the sludge into the body of sludge in the lower tank.

21. In the event that the sludge falls below the level of the pipe 70 in the tank 41 and oil enters this pipe, the oil will not flow downwardly due to the fact that the tank 42 is under slightly higher pressure than the tank 41. The sludge will, however, flow 125 downwardly due to its being heavier than 130

the oil and the body of the sludge 64 is automatically maintained.

Partially treated kerosene is then taken from the top of the tank 41 through a pipe 71 and delivered into an injector 72 which takes sludge from a body of sludge 73 in the bottom of the tank 40, this sludge and oil being mixed in a pipe 74 and delivered through distributor 75 into the tank 40. Cleaned oil is delivered from the tank 40 through a pipe 76 in the extreme top thereof.

The level of the sludge in the tank 40 is maintained by constantly supplying acid through a pipe 80 and by supplying a pipe 15 81 which connects into the tank 40 at the desired level of the sludge delivering the acid sludge into the body of sludge 64 in the tank 41. In the event that the level of the body of sludge 73 falls below the inlet end 20 of the pipe 81, oil starts to flow into this pipe but the flow ceases almost immediately due to the fact that the tank 41 is under higher pressure than the tank 40 which can only be overcome due to the fact that the 25 acid is heavier than the oil.

It will be seen that the fresh oil introduced into the pipe 50 is first treated with very nearly spent sludge, the sludge in the body of sludge 52 being much more nearly spent than the sludge at 64, and the sludge 64 being much more nearly spent than the sludge at 73. Fresh acid is supplied through the pipe 80; the result is that the oil is successively treated with a higher activity of acid, being finally treated with fresh acid in the tank 40. By thus passing the acid in one direction through the device in counter-current with the flow of oil, a very high economy of acid consumption is obtained. 40 The form of my invention last above described, is specifically claimed in a co-pending application Serial No. 713,339, filed May 14, 1924.

In the previous description of the operation and utility of my invention the separation of the heavy reagent from the kerosene is accomplished by centrifugal action and gravity. It will be readily understood, however, that various means of separating the fluids may be employed such as by velocity impact or centrifugal separation. In the apparatus shown diagrammatically in Fig. 5 the reagent is taken from a reagent container 90 through a pipe 91 which leads into an injector casing 92. This reagent is drawn from the tank 90 by the injector action of a flow of kerosene from a nozzle 93 to which the kerosene is delivered through a pipe 94 and a valve 95, which flow of kerosene carries with it a quantity of reagent through the constricted orifice 96 wherein the two fluids are brought into very intimate relationship. The reagent and kerosene mixture then flows through pipe 98 to a separator 99 which may be of any of the above de-

scribed forms. In this separator a thorough separation of the reagent from the kerosene takes place, the reagent being delivered through piping 100 to the reagent tank 90 and the kerosene being conducted through piping 102 to the other treating apparatus or storage tanks.

In the form of apparatus suitable for the practice of my invention, shown in Fig. 6, a primary separating tank 105 is employed 75 in which the charge of reagent is originally placed by means of piping 106, this reagent being maintained in the tank 105 at a level substantially as indicated at 107. In this apparatus the reagent is drawn from the 80 bottom of the tank 105 through piping 108 by the injector action of a flow of kerosene under pressure from a nozzle 109. The reagent and the kerosene are then subjected to the hereinbefore described combining 85 action accomplished by their passage through a constricted channel 110 from which they are delivered through piping 112 into the upper part of the tank 105. In this tank such portions of the reagent, which are in 90 large enough drops to separate by gravity from the kerosene, drop downwardly in the tank 105 and combine with the reagent in the bottom thereof, while those portions of the reagent which are so intimately mixed 95 with the kerosene that they will not separate readily by gravity are carried through piping 115 to a separator 116 from which the reagent is returned to the tank 105 through pipe 117 and the kerosene forwarded to 100 other apparatus or storage tanks through piping 118.

In the practice of my invention with equipment of the character indicated at Figs. 5 and 6, it may be desirous to employ 105 several sets of equipment such as shown in either Figs. 5 or 6, through which the kerosene is consecutively conducted, and in which the kerosene is subjected to reagents of gradually increasing strength, or of varying 110 characteristics, thus making it possible to introduce crude or impure kerosene at one end of the system and to withdraw it from the opposite end thereof in a condition ready for sale.

While I have described my invention as used in the treatment of kerosene by means of acid, I do not wish to be understood as thereby intending to limit myself to this particular application but, on the contrary, 115 wish it to be distinctly understood that my invention is defined solely by the attached claims.

I claim as my invention:

1. In a continuous method of refining oil, 125 steps for intimately mixing the oil with a reagent heavier than and insoluble in the oil and for repeatedly utilizing the reagent, said steps comprising: maintaining a layer of reagent in a substantially closed vessel, to any 130

certain level below the top thereof, the remainder of space in the vessel containing oil; continuously introducing fresh reagent into said vessel; continuously withdrawing spent reagent at such rate as to maintain the level of reagent; continuously injecting into the vessel a confined stream of raw oil under pressure by a pressure producing means; inducing into and solely by means of the said oil stream a stream of reagent from the reagent within said vessel; intermixing the two streams while confined solely through the agency of the velocity-energy of the stream of raw oil, said induction and intermixing taking place beyond and on the discharge side of the pressure producing means, and discharging the intermixed streams into the same vessel for circulating and repeatedly intermixing the reagent with the raw oil, the treated oil and the reagent continuously separating by gravity difference; and continuously discharging treated oil from the top of the vessel at a rate substantially equal to the rate of feed of raw oil.

2. A process of the character defined in claim 1, in which the two streams are turbulently intermixed, solely through the agency of the velocity-energy of the stream of raw oil.

3. A process of the character defined in claim 1, in which the intermixed streams are discharged into the vessel at a point above the upper surface of the reagent layer and below the upper surface of the oil layer.

4. A process of the character defined in claim 1, in which a plurality of streams of raw oil under pressure are injected into a chamber communicating with the vessel, each of such streams inducing into itself a stream of reagent from such reagent body and each of the combined streams being intermixed through the agency of the velocity-energy of the stream of raw oil making part of such combined stream.

5. An apparatus for continuously treating oil with reagent heavier than and insoluble in the oil, such apparatus comprising: a substantially closed vessel provided with an inlet for fresh reagent, a valve controlled outlet at the bottom of the vessel for spent reagent, an outlet for treated oil at the top of the vessel, a pipe for conveying raw oil under pressure into the vessel and an aspirating injector into which said pipe discharges, said injector communicating on its suction side with the lower part of the vessel.

6. An apparatus for continuously treating oil with a reagent heavier than and insoluble in the oil, such apparatus comprising: a substantially closed vessel provided with an inlet for fresh reagent, a valve controlled

outlet at the bottom of the vessel for spent reagent, an outlet for treated oil at the top of the vessel, a pipe for conveying raw oil under pressure into a plurality of aspirating injectors, which injectors communicate on their suction side with the lower part of the vessel and also communicate with the vessel at a point above the point of communication of the suction side of said injectors with the vessel.

7. An apparatus for continuously treating oil with a reagent heavier than and insoluble in the oil, such apparatus comprising: a substantially closed vessel provided with an inlet for fresh reagent, an outlet for treated oil at the top of the vessel, a pipe for conveying raw oil under pressure into a plurality of aspirating injectors, which injectors communicate on their suction side with the lower part of the vessel and discharge each into a bent pipe, which pipes communicate with the vessel at a point above the point of communication of the suction side of said injectors with the vessel.

8. An apparatus for continuously treating oil with a reagent heavier than and insoluble in the oil, such apparatus comprising: a substantially closed vessel provided with an inlet for fresh reagent, an outlet for treated oil at the top of the vessel, a pipe for conveying raw oil under pressure into a plurality of injectors, which injectors communicate on their suction side with the lower part of the vessel and discharge each into a bent pipe, which pipes discharge into the vessel at a point above the point of communication of the suction side of said injectors with the vessel, each of such pipes being provided with a stop valve for the closure thereof.

9. An apparatus for continuously treating oil with reagent heavier than and insoluble in the oil, said apparatus comprising: a substantially closed vessel provided with an inlet for fresh reagent, a valve controlled outlet at the bottom for spent reagent, an outlet for treated oil at the top of the vessel, an injector comprising a hollow body and a jet inside said body and in annular relation thereto, a pipe for conveying raw oil under pressure into said jet, a pipe communicating with the lower portion of the vessel for conveying reagent from said vessel into the annular space between said jet and said body and into admixture with said oil stream, and a confining channel for conveying the oil and the reagent from the injector into said vessel and for completing the admixture of said oil with said reagent.

In testimony whereof, I have hereunto set my hand at Los Angeles, California

SAMUEL J. DICKEY
